[57] CLAIM

The ornamental design for a home theater in-wall storage unit, as shown and described.

DESCRIPTION

FIG. 1 is a top, front, and left side perspective view of a home theater in-wall storage unit showing our new design; FIG. 2 is an enlarged top plan view thereof, the bottom being a mirror image of that shown;

FIG. 3 is an enlarged right side elevational view thereof, the left side being a mirror image of that shown;

FIG. 4 is an enlarged front elevational view thereof;

FIG. 5 is a top, front, and left side perspective view thereof, with the right door shown in an opened position;

FIG. 6 is an enlarged top plan view thereof, with both doors shown in an opened position;

FIG. 7 is an enlarged right side elevational view thereof, with both doors shown in an opened position, and the left side being a mirror image of that shown; and,

FIG. 8 is an enlarged front elevational view thereof, with both doors shown in an opened position.

The fragmentary broken-line disclosure of a portion of the wall surrounding the unit is for illustrative purposes only and forms no part of the claimed design.
